COVER FOR TOILET SEATS OR LIDS

Filed Feb. 13, 1948

UNITED STATES PATENT OFFICE

2,611,136

COVER FOR TOILET SEATS OR LIDS

Maurice L. Diamond, Bronx, N. Y.

Application February 13, 1948, Serial No. 8,047

2 Claims. (Cl. 4—242)

1

This invention relates to toilet seat or lid covers.

In heretofore known toilet lid covers the anchorage of the cover was rather loose and not adjustable and did not comply with the practical requirements as to the various standard sizes of toilet lids. The present invention tends to overcome these and other disadvantages and has as one of its objects the provision of means for yieldably affixing a cover to such lid.

It is another object of the present invention to provide a simple construction for the cover of the toilet lid which will fit various standard sizes of the latter, is inexpensive to manufacture and easy to handle.

Still another object of the present invention is to provide means permitting a certain degree of give to the cover of the lid whereby the cover may be readily conformed to the shape of the particular lid to which it is applied.

It is a further object of this invention to provide simple anchoring or attaching means in the form of snap fasteners and the like which facilitate instantaneous application of the cover to and removal from the toilet lid.

These and other objects of the invention will be pointed out in the following description and claims and illustrated in the accompanying drawing which discloses, by way of example, the principle of the invention and preferred modes which have been contemplated for applying said principle.

In the drawing:

Fig. 1 is a bottom plan view of the toilet lid cover per se.

Fig. 2 shows the lid cover of Fig. 1 in applied condition.

Fig. 3 is a cross-section taken along line 3—3 of Fig. 2.

Fig. 4 shows in modified form the lid cover in applied condition, part of which being in the process of being affixed to the toilet lid.

Referring now more particularly to the drawing, there is shown in Fig. 1 a bottom view of a lid cover 10 made from a suitable pliable fabric material. The inner circumferential edge 11 of the cover 10 carries an elastic ribbon or band 12 forming a binding, which may be suitably shaped in order to conform the same to the outline of the circumferential edge 11. The rearward end 13 of cover 10 projects beyond the edges 14, 15 of the elastic binding 12 and has attached thereto a web 16 made from rubber or other suitable elastic or stretchable material. This web or tongue 16 is stitched along seam 17, either to the

2

underside or to the end of the top surface of cover 10. The free end of web 16 is reinforced by a fold 18 and carries at opposed ends fastening means in the form of snap buttons 19, 20.

5 As can be further seen from Fig. 1, male snap buttons 21, 22, complementary to snap buttons 19, 20, are attached adjacent the ends 14 and 15 of elastic binding 12. At a predetermined distance from the male snap buttons 21, 22 are further arranged on binding 12 male snap buttons 23, 24 for a purpose later described.

Fig. 2 shows the cover of Fig. 1 in applied condition on a toilet lid 25 which has an extension 26 through an opening 27 of which a hinge bolt (not shown) may extend in transverse direction for swingable movement of the lid with respect to the toilet seat. Web 16, as can be seen from Fig. 2, is swung around the forward end of extension 26 so that snap buttons 19, 21 and 20, 22 become engaged and hold cover 10 firmly but somewhat yieldably on lid 25.

If it is now desired to apply the lid cover 10 to a different kind of lid 30 which is not provided with an extension 26 but is rather of the old and standard type having a somewhat more round configuration terminating in a substantially flat rear part 30a, all that is to be done is to forwardly move web 16 at the underside of the lid 30 to a position at which the snap buttons 19, 20 come to lie substantially in alignment with snap buttons 23 and 24. In this position it is proposed in accordance with the invention to hold web 16 in place by means of a strap member 31 having the outer snap buttons 23a, 24a and the intermediate snap button parts 19a, 20a. Snap buttons 19a and 20a are male buttons which engage the respective female snap buttons 19 and 20 of web 16, whereas snap buttons 23a and 24a become engaged with the male buttons 23 and 24 of the cover 10.

40 In order to further obtain a substantially firm anchorage of the cover on toilet lid 30, it is further suggested to employ a strap member 32 extending from snap button 21 of the cover to snap button 22. Strap 32 carries corresponding female buttons 21a and 22a for the engagement of the complementary snap button parts 21 and 22. If desired, strap members 31 and 32 may also be made of an elastic, stretchable material. Instead of a single strap 31, two straps may be employed which extend, respectively, between buttons 24 and 20 on the one hand and 19 and 23 on the other hand.

45 As can be further seen in Fig. 4, appropriate holes 33 and 34 are provided at the underface

30b of lid 30 to attach the lid holders by means of screws (not shown) in the conventional manner.

It can thus be seen that there has been provided in accordance with this invention a cover for a toilet lid comprising a body of pliable material having a rear end and a circumferential edge, said body extending to cover the entire upper surface of said lid and projecting with said circumferential edge to the underface of said lid, an elastic strip forming the binding of said circumferential edge of said body, a web of elastic material extending from said rear end of said body therebeyond and adapted to be folded for position adjacent said binding, and respective means fixed to said binding and to said web to detachably connect said web to said binding to thereby anchor said cover on the underface of said lid and to retain said cover on the latter.

In contradistinction to conventional lid covers the present structure is characterized by a circumferential edge 11 along which an elastic element 12 extends, which terminates at a rearward extension 13 adapted to rest upon the lid extension 26 whence web 16 projects as illustrated in Fig. 3.

Although the invention has been described with reference to certain specific embodiments thereof, it is to be distinctly understood that various modifications and adaptations of the arrangements herein disclosed may be made and may readily occur to persons skilled in the art without constituting a departure from the spirit and scope of the invention as defined in the objects and in the appended claims.

Having thus described the invention, what is claimed as new and desired to be secured by Letters Patent, is:

1. A cover for a toilet lid having a rear end,

comprising a body of a substantially pliable material shaped for position over the surface of said lid and having a circumferential edge extending for position underneath said surface, said circumferential edge terminating in two spaced apart ends, an extension piece connected with said body and of such dimension to extend around said rear end of said lid, and respective complementary fastening means adjacent said ends of said circumferential edge and associated with said extension piece, said circumferential edge being provided with elastic binding means whereby said body may be conformed to the shape of and held in position below the surface of said lid, said extension piece being made of a substantially resilient material and adapted to extend over a part of the underface of said lid around said end thereof for connection with said circumferential edge by means of said fastening means.

2. A cover for a toilet lid according to claim 1, wherein said extension piece is made of an elastic web adapted to be stretched in lengthwise direction of said lid.

MAURICE L. DIAMOND.
